(57) **CLAIM**

The ornamental design for a recumbent bicycle, as shown and described.

DESCRIPTION

FIG. 1 is a first left side isometric view of a recumbent bicycle according to the present invention.

FIG. 2 is a left side view of the recumbent bicycle according to the present invention.

FIG. 3 is a second left side isometric view of the recumbent bicycle according to the present invention.

FIG. 4 is a right side view of the recumbent bicycle according to the present invention.

FIG. 5 is a back side view of the recumbent bicycle according to the present invention; and,

FIG. 6 is a front side view of the recumbent bicycle according to the present invention.

The broken lines shown in the drawings illustrate portions of the recumbent bicycle that form no part of the claimed design.
